United States Patent Office

Des. 223,218

Patented Mar. 28, 1972

223,218

PROPELLER

LeRoy Martens, Lake Crystal, Minn., assignor to Lar-Mar-Co. Props, Incorporated, Lake Crystal, Minn.

Filed Oct. 24, 1969, Ser. No. 19,716

Term of patent 14 years

Int. Cl. D12—14

U.S. Cl. D71—1

FIG. 1 is a rear end elevational view of a propeller embodying my design;

FIG. 2 is a front end elevational view of the same;

FIG. 3 is a side elevational view of the same; and

FIG. 4 is a side elevational view of the same rotated 60° from the position of viewing in FIG. 3.

I claim:

The ornamental design for a propeller, as shown and described.
